UNITED STATES PATENT OFFICE.

WILLIAM GRISCOM, JR., OF PHILADELPHIA, PENNSYLVANIA.

DESIGN FOR A BLOCK OF MAGNESIA.

SPECIFICATION forming part of Design No. 14,842, dated March 4, 1884.

Application filed December 17, 1883. Term of patent 7 years.

To all whom it may concern:

Be it known that I, WILLIAM GRISCOM, Jr., a citizen of the United States, and a resident of Philadelphia, Pennsylvania, have invented or produced a new and original Design for a Block of Carbonate of Magnesia, of which the following is a specification.

My design for a cake of carbonate of magnesia is fully shown in the accompanying drawings; and it consists of a polygonal block with ribbed faces.

In the drawings are shown blocks of various forms, Figure 1 being a perfect cube; Fig. 2, an oblong block; Fig. 3, a hexagonal block, and Fig. 4, a triangular block; but in all of these

cases the essential feature of the design—the ribbing of the surfaces of the block—is the same.

I claim—

The within-described design for a cake of carbonate of magnesia, said design comprising a block of polygonal shape having all of its faces ribbed, as shown and described.

In testimony whereof I have signed my name to this specification in the presence of two subscribing witnesses.

WILLIAM GRISCOM, JR.
